UNITED STATES PATENT OFFICE.

JOHN SHIPLEY, OF COUNCIL BLUFFS, IOWA, ASSIGNOR OF ONE-HALF TO
GEORGE D. CRUM, OF SAME PLACE.

WIRE-STRETCHER.

SPECIFICATION forming part of Letters Patent No. 363,176, dated May 17, 1887.

Application filed March 7, 1887. Serial No. 229,92. (No model.)

To all whom it may concern:

Be it known that I, JOHN SHIPLEY, a citizen of the United States, residing at Council Bluffs, in the county of Pottawattamie and State of Iowa, have invented certain new and useful Improvements in Wire-Stretchers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to wire-stretchers, and has for its object the construction of a device which will facilitate the stretching of the wires or strands in the setting up of wire or similar fences by providing a means for taking up the slack in the wire and provisions which will retain such wire when partially stretched in case it becomes necessary to obtain a fresh grip, and will hold the wire, when stretched, during the operation of securing it to the posts 25 or splicing the two ends together.

The improvement consists in the novel features hereinafter more fully described, claimed, and shown in the annexed drawings, in which—

Figure 1 is a plan view of a wire-stretcher 30 embodying my invention reduced to practice; Fig. 2, a perspective detail view showing its application for splicing the ends of the two wires.

The resistance-lever A is constructed so that 35 its inner end, a, can obtain a purchase upon a post or other support, and for this purpose the end a is curved and sharpened to fit about or bite into the post, as desired, and is claw-shaped to receive and hold a wire.

40 To the outer end is pivotally connected the inner end of the wire-gripping lever B, which has its outer end, b, bent approximately at right angles and terminating in a claw to grip the wire. The hand-lever C, pivoted to the resistance-lever A at a point between its ends, is connected by rod D with the wire-gripping 45 lever B. The lock-bar E, carried by the resistance-lever, is provided with a series of perforations, e, one of which is adapted to fit over the stop f and hold the wire when stretched.

The wire-retainer is composed of the chain or connection g, secured at its inner end to the resistance-lever near its claw-shaped end a, and the claw-shaped retaining-hook G. The outer portion of the resistance-lever A is separated or divided, and the hand and wire-gripping levers are secured between these divided parts, so as to have a support both above and below, and the connecting-bar D, passed between said divided parts, is bifurcated at each end and embraces the respective levers. In practice the end of the resistance-lever is placed against the post or other support, and the wire to be stretched is held by the gripping-lever, the hand-lever is pressed toward the support or post, and if the wire be not sufficiently taut when the hand-lever reaches the limit of its movement, the wire is caught and held by the wire-retaining hook till the wire-gripping lever is carried back and obtains a fresh grip. When the wire is drawn taut, it is held by the locking-bar which is passed over the stop on the hand-lever. For securing the ends of two wires, one is held by the claw of the resistance-lever and the other wire held by the gripping-lever, and the movement of the hand-lever brings the ends together, which are held by the lock-bar, as will be readily appreciated.

Having thus described my invention, what I claim, and desire to secure by Letters Patent, is—

1. A wire-stretcher composed of a resistance-lever, the wire-gripping lever pivotally secured to the outer end of the resistance-lever, 85 the hand-lever secured at its inner end to the resistance-lever between its ends, the connecting-rod extended across the resistance-lever and connected at its ends with the hand-lever and the wire-gripping lever, respectively, the lock-bar interposed between the resistance and the hand levers, and the wire-retainer for holding the wire partially stretched while the wire gripping lever is obtaining a fresh purchase upon the wire, substantially as described. 95

2. The combination, with the resistance-lever and the wire-gripping lever carried by the outer end of the resistance-lever, of the hand-lever pivotally connected with the resistance-lever between its ends, the connect- 100

ing-rod crossed over the resistance-lever and united at its ends with the wire-gripping and hand levers, respectively, and the lock-bar interposed between the hand and resistance levers, substantially as set forth.

3. The combination, with the resistance-lever having a claw-shaped end, and the wire-gripping lever pivotally connected at one end with the outer end of the resistance-lever and terminating at its free or opposite end in a claw, of the hand-lever connected with the resistance-lever, the connecting-rod uniting the hand and wire-gripping levers, the stop on one lever, and the lock-bar pivotally secured to the other lever and provided with a series of openings, any one of which is adapted to engage with said stop, substantially as set forth.

4. The combination of the resistance-lever having its outer portion separated or divided, the hand and wire-gripping levers pivoted between the divided parts, and the connecting-

rod passed between said divided parts, and having its ends bifurcated and embracing the wire-gripping and hand levers, respectively, substantially as and for the purpose specified.

25

5. The combination of the resistance-lever having a claw-shaped end, the wire-grip lever mounted upon the outer end thereof, the hand-lever secured at its inner end to the resistance-lever between the ends thereof, the connecting-rod placed crosswise of the resistance-lever and uniting the hand and wire-gripping levers, the lock-bar having a series of openings, the stop, and the wire-retainer composed of the connection and the wire-gripping hook, substantially as described.

30

In testimony whereof I affix my signature in presence of two witnesses.

JOHN SHIPLEY.
